UNITED STATES PATENT OFFICE.

CHARLES H. FOSTER, OF NEW YORK, N. Y., ASSIGNOR TO THE UNION SPECIAL SEWING MACHINE CO., OF CHICAGO, ILLINOIS, A CORPORATION OF ILLINOIS.

APPARATUS FOR DELIVERING FILLED BAGS TO SEWING-MACHINES.

No. 875,339.

Specification of Letters Patent.

Patented Dec. 31, 1907.

Application filed May 11, 1901. Serial No. 59,822. Renewed May 7, 1907. Serial No. 372,343.

To all whom it may concern:

Be it known that I, CHARLES H. FOSTER, a citizen of the United States, residing at New York, in the county of New York, State 5 of New York, have invented certain new and useful Improvements in Apparatus for Delivering Filled Bags to Sewing Mechanism, of which the following is a description, reference being had to the accompanying drawing and to the letters and figures of reference 10 marked theron.

My invention relates to an improvement in apparatus for sewing filled sacks, and particularly to mechanism for supporting and 15 delivering the same at proper and uniform speed to the stitch forming mechanism of a sewing apparatus, such as a sewing machine.

In a patent heretofore granted to Lansing Onderdonk, No. 583,388, dated May 25th, 20 1897, there is shown and described, an arrangement for supporting, feeding and sewing up the mouths of filled sacks, in which a sewing machine is arranged in a substantially vertical position, so that its needle bar 25 runs horizontally, and the bags are fed at proper speed with their tops between the presser foot and opposing bed plate, and sewed by the stitch forming mechanism. The sewing machine illustrated herein is 30 the same as that illustrated in said Patent 583,388, which machine proper is shown described and claimed in Patents 547,675 and 547,676, granted October 8th, 1895, and known as the Union Special Cylinder Machine.

The object of the present invention is to provide an apparatus which shall be comparatively simple, very durable, and effective, for supporting and feeding the filled 40 bags or sacks to the stitch forming mechanism of the machine and then carrying them beyond, where they can be readily removed by the operator, the speed being regulated according to the speed of the machine, and 45 the feeding support for the bags being adjustable to accommodate the different sizes of bags.

The invention consists in the various matters hereinafter described and referred to in 50 the appended claims.

The invention is illustrated in the accompanying drawings, in which

Figure 1 is a perspective view of an apparatus embodying my invention; and Fig. 2 55 is a front view, partly in section, certain of

the parts being broken away for the sake of clearness of illustration.

In these drawings, the sewing mechanism is herein embodied in a sewing machine of the Union Special type, such as illustrated in 60 Patents 547,675, and 547,676, above referred to, and is represented by the letter A. It is attached to a table or support B, of any suitable construction, the driving shaft thereof being arranged vertically, and the goose 65 neck C, overhanging the edge of the table or support, the needle D working in a horizontal plane; the parts being of well known construction, they need not be more specifically referred to.

The supporting table is preferably made of T-iron or constructed as shown in Fig. 1, with suitable legs E. On the under side of the table is supported a counter shaft F, having the usual cone and band pulleys and 70 clutch mechanism on it, to which power is applied to drive the machine, a belt a passing over one of the cone pulleys serving to transmit motion to the belt wheel on the driving shaft of the sewing machine.

A belt b runs from a small cone on the under driver, over an idler pulley j to a pulley H, on the upright shaft Q journaled in upper and lower bearings G, G; a center screw p working in the lower end of the 75 upright shaft Q, to take up the wear. This upright shaft is provided with a worm e, splined upon it, adapted to slide up and down thereon, it being carried up and down on the shaft by the movement of the bracket d, which is 80 supported by, and moves up and down with, the bracket i, provided with a long boss on its inner face, in which is journaled the shaft k upon which is mounted the worm wheel f 85 meshing with the worm e. The hubs of the belt pulleys g, are fast on the shafts k, the conveying belt h running over said pulleys, and as the upright shaft Q revolves, the worm wheel f will revolve, and move the conveyor belt over the pulleys, thus conveying 90 the bags containing sugar, salt, or other material, to the stitch forming mechanism of the sewing machine, the connections between the common driving mechanism and the driving shaft of the sewing machine and 95 the upright shaft Q insuring the proper co-operative speed relation of the conveying belt or endless carrier h, and the stitching mechanism.

It will be seen that as the gooseneck and 100 the upright shaft Q are arranged to the project to

head of the machine, carrying the needle mechanism overhang the edge of the table and the shafts *k*, project also beyond the table, that the conveyer is outside the framework of the support and this makes a construction exceedingly convenient for the operator.

The bracket *i* upon which the conveying belt pulleys are supported, and which is 10 preferably adjustable up and down to accommodate varying sizes of bags, is herein shown as suitably embracing the front legs or standards of the supporting table or framework, and near each end has attached to it 15 one end of sprocket chains *K*, *K*, which pass over sprocket wheels *L*, *L*, on opposite ends of the shaft *m*. Counterweights *M*, at the lower ends of the chains serve to aid in the upward movement of the bracket *i*, while the 20 pawl *n* working in the ratchet wheel *o* on the shaft *m* holds the bracket in the position to which it is adjusted.

The end of shaft *m* is formed to receive a crank *N*, or otherwise adapted to be rotated by hand, so as to raise or lower the bracket *i*, which carrying the bracket *d*, causes the worm wheel *e* to slide up and down on the upright shaft *Q*, as well as the worm wheel *f* meshing therewith.

30 It will be understood that I do not wish to be limited to the exact details of construction herein shown and described, as various minor modifications and changes may be made without departing from the spirit of 35 my invention.

Having thus described my invention, what I claim as new and desire to secure by Letters Patent, is:

1. In an organized sewing machine for 40 feeding and sewing filled sacks, a suitable supporting framework, a sewing mechanism thereon, a driving shaft, a horizontal conveying mechanism, connections between the driving shaft and the sewing mechanism and 45 between the driving shaft and the conveying mechanism, said means including a vertical shaft having a gear rotating therewith, but slideable thereon and a horizontal shaft having a gear meshing with said slideable gear, and 50 means for raising and lowering the horizontal shaft and thereby the gear on the vertical shaft; substantially as described.

2. In an apparatus for feeding and sewing 55 filled sacks, a suitable supporting framework, a sewing mechanism thereon, a driving shaft, connections between the driving shaft and the sewing mechanism, a conveying mechanism for the sacks, including a vertically moving bracket with means for adjusting it, shafts carried thereby, an endless band trained over said shafts, one of said shafts being provided with a worm wheel, a 60 vertical shaft provided with a vertically movable worm engaging said worm wheel, 65 whereby in the adjustment of the bracket,

the worm is also adjusted; substantially as described.

3. An apparatus for feeding and sewing filled bags, including a sewing mechanism, a horizontally disposed conveying mechanism 70 in proper coöperative relation thereto, a driving mechanism, connections between the same and the sewing mechanism, and connections between said driving mechanism, and the conveying mechanism, said latter 75 connections including an upright shaft, and gearing between the same and the conveying mechanism; and means for raising and lowering the conveying mechanism with the gearing, substantially as described. 80

4. An apparatus for feeding and sewing filled bags, including a sewing mechanism, a horizontally disposed conveying mechanism in proper coöperative relation thereto, a driving mechanism, connections between the 85 same and the sewing mechanism, and connections between said driving mechanism, and the conveying mechanism, said latter connections including an upright shaft carrying a worm, a worm wheel meshing therewith, and connections between the worm wheel, and conveying mechanism; substantially 90 as described.

5. An apparatus for feeding and sewing filled bags, including a sewing mechanism, a 95 conveying mechanism in proper coöperative relation thereto, a driving mechanism, connections between the same and the sewing mechanism, and connections between the driving mechanism and the conveying mechanism, said latter connection including an 100 upright shaft operatively connected to the driving mechanism, a worm movable on said upright shaft, a movable bracket having transverse shafts, belt pulleys on said shafts, 105 a conveyer belt on said pulleys, and a worm wheel on one of said shafts, meshing with the worm gear on the upright shaft; substantially as described.

6. An apparatus for feeding and sewing 110 filled bags, including a sewing mechanism, a conveying mechanism in proper coöperative relation thereto, a driving mechanism, connections between the same and the sewing mechanism, and connections between the 115 driving mechanism and the conveying mechanism, said latter connection including an upright shaft operatively connected to the driving mechanism, a worm splined on said upright shaft and movable vertically thereon, 120 a bracket having transverse shafts, belt pulleys on said shafts, a conveyer belt on said pulleys, a worm wheel on one of said shafts meshing with the worm gear on the upright shaft, and means for raising and lowering 125 the conveyer mechanism; substantially as described.

7. In the herein described apparatus, an upright shaft, means for driving it, a bracket supporting an endless conveyer, and con- 130

nections between the upright shaft and the conveyer for driving the latter, and means for raising and lowering the bracket and with it the conveyer, said means including a shaft 5 carrying pulleys, chains or belts running over said pulleys, and at one end attached to the bracket, and means for rotating the shaft; substantially as described.

8. In an apparatus of the character described, a sewing mechanism and a conveyer mechanism, both operated from the same driving mechanism at proper relative speed, the intermediate connections between the driving mechanism and the conveyer 10 mechanism, including a rotating upright shaft, a worm adjustable thereon, a worm wheel in engagement therewith, and a support for the conveyer, carrying a shaft upon which the worm wheel is mounted, said 15 shaft being arranged to drive the conveyer; substantially as described.

9. In an apparatus of the character described, a sewing mechanism and a conveyer mechanism, both operated from the same 20 driving mechanism at proper relative speed, the intermediate connections between the

driving mechanism and the conveyer mechanism, including a rotating shaft, a worm thereon, a worm wheel in engagement therewith, and a support for the conveyer, carrying a shaft upon which the worm wheel is mounted, said shaft being arranged to drive the conveyer, and means for raising and lowering the conveyer; substantially as described. 30

10. In an apparatus of the character described, a conveyer for the articles to be sewed, and means for adjusting said conveyer, comprising a bracket upon which the conveyer is supported, sprocket chains attached at one end to said bracket, a shaft, sprocket wheels upon opposite ends of said shaft over which said sprocket chains are trained, and a pawl and ratchet mechanism for holding the bracket in position to which 40 it is adjusted; substantially as described. 45

In testimony whereof I affix my signature, in presence of two witnesses.
